UNITED STATES PATENT OFFICE.

WALTHER FRITZ, OF BERLIN, GERMANY, ASSIGNOR TO GENERAL ELECTRIC COMPANY, A CORPORATION OF NEW YORK.

TURBINE.

No. 916,438.

Specification of Letters Patent. Patented March 30, 1909.

Application filed August 7, 1907. Serial No. 387,547.

To all whom it may concern:

Be it known that I, WALTHER FRITZ, a subject of the Emperor of Germany, residing at Berlin, Germany, have invented certain new and useful Improvements in Turbines, of which the following is a specification.

The present invention relates to the construction of elastic fluid turbines and more especially to those intended for marine propulsion wherein sets of forward driving and reversing buckets are provided whereby the vessel may be propelled in a forward or reverse direction as desired.

15 The object of my invention is to improve the construction of turbines of the above mentioned type.

For a consideration of what I believe to be novel and my invention, attention is directed to the accompanying specification and to the claims appended thereto.

In the accompanying drawings which are illustrative of one of the embodiments of my invention, Figure 1 is a side elevation of the high pressure end of the turbine with the upper portion in section; Fig. 2 is a side elevation of the low pressure and reversing portion of the same turbine with the upper portion in section; and Fig. 3 is a longitudinal section of the rotor.

The casing of the turbine is divided on an axial plane into two principal parts, 1 and 2. Each of these parts is further divided into sections in planes perpendicular to the axis 35 for convenience in installing the same on board ship and also to facilitate manufacture and transportation. For example, each half of the casing is divided into a high pressure section 3, a low pressure section 4, 40 and a reversing section 5. The lower half of the casing is provided with flanges 6 that rest on and are secured to the foundation supported by the frame of the ship. Mounted at the ends of the casing are self-aligning 45 shaft bearings 7 and 8. On the high pressure end is provided a thrust bearing 9 to take up the thrust on the main shaft. The propeller, not shown, is mounted on the shaft at the low pressure end. Usually a 50 coupling will be inserted between the turbine and the portion of the shaft carrying

the propeller. Adjacent each bearing and driven by the main shaft are pumps 10 and 11 for supplying lubricant to the bearings under pressure.

55 Located in the high pressure end of the casing are diaphragms 12 which divide it into compartments or stages, each compartment containing a wheel 13 having rows of wheel buckets 14 acting by impact. Between the rows of wheel buckets are rows of intermediate buckets 15; the arc of the wheel covered by the intermediates increasing from the high toward the low pressure end of the turbine. As arranged the first four stages 60 are provided with a greater number of rows of wheel buckets than are the subsequent jet stages. Steam or other elastic fluid is admitted under high pressure to the first wheel by the sectionalized expanding nozzle 16 65 from the conduit 17 in the steam chest. Between each of the subsequent jet or impact stages are stage nozzles 18 carried by the diaphragms. These nozzles may be expanding or non-expanding in character, usually 70 the latter, in order to have relatively low fluid velocities.

75 Formed in the top of the upper half of the casing are conduits 19, 20 and 21 whereby the earlier stages may be shunted or rendered ineffective under certain conditions.

In the low pressure portion of the turbine the motive fluid acts by reaction, and for this reason the intermediate buckets extend entirely around the rotating element, and all 80 of the buckets on the latter are consequently active. The low pressure portion of the casing 4 is also provided with an exhaust conduit 22 that is common to both the forward and reversing buckets. A part of the conduit is formed in the lower half of the casing and the remainder in the upper portion, the discharge opening being at the top.

85 It is to be noted that the later or low pressure rows of buckets for forward driving and reversing extend well into the exhaust conduit, the object being to reduce the axial dimension of the turbine and also to provide for an unobstructed exhaust. I mount the stationary or intermediate 90 buckets in this portion of the turbine on annular flanges 23 and 24 formed on the cas-

ing which extend toward each other. These flanges are usually unsupported at their adjacent ends to reduce troubles due to distortion to a minimum but they may be supported from the walls of the conduit if desired.

The reversing portion of the turbine comprises a plurality of jet or impact stages, three being shown in the present illustration, 10 and annular low pressure stages operating on the reaction principle, the buckets of the latter being mounted on the support of smaller diameter than that of the jet stages.

15 Steam or other elastic fluid is admitted to the reversing buckets by a chest 25 that covers something less than the full circumference of the first wheel. This chest discharges fluid to the sectionalized nozzle 26. 20 Between the stage or wheel compartments and supported by the diaphragms 27 are sectionalized stage nozzles 28. The admission and stage nozzles may be expanding or non-expanding in character. These nozzles 25 are set in the reverse direction to those in the forward driving portion of the turbine, and so also are the buckets of the high and low pressure reversing stages.

It is evident that the construction of the 30 rotating element of the turbine must be such that it will be exceedingly stiff to resist the whipping action to which structures of this kind are subjected, and also that it must be as light as possible consistent with the work 35 to be performed. To this end the shaft is made up of three principal sections 29, 30 and 31. The section 29 is made hollow and the diameter increases step-by-step toward the low pressure end. The intermediate 40 section 30 is composed of a cylinder having inturned flanges 32 which are bored to receive shoulders 33 on the outer shaft sections. These shoulders serve to center the parts and to assist in holding them together. 45 Adjacent the inturned flanges on the cylinder are outturned flanges 34 on the outer shaft sections through which clamping bolts pass into the flanges 32. The shaft section 31 is substantially the same in construction 50 as the section 29 except that it is shorter. The steps on section 29 are long enough to receive the hubs of two wheels, and in some instances three. Around the hubs and between them and the bores of the diaphragm 55 are packings 35. The wheels are secured to the shaft by nuts which force the hubs up against shoulders thereon.

Surrounding the cylinder section 30 of the shaft is a drum composed of two principal parts 36 and 37. Part 36 is provided with an internal flange 38 that is engaged by a spider 39, the latter being shouldered to assist in holding the parts in place and is seated with a driving fit on the cylinder 60 65 30. Bolts are employed to secure the flange

38 to the spider. On the right hand or high pressure end of the part 36 is an annular flange 40 that acts as a support for the wheel buckets of the last one of the jet stages. The part 37 of the drum is smaller 70 in diameter than the part 36 and is provided with a hub or spider 41 that makes a driving fit with the cylinder 30. The right hand end is flared outwardly to form a flange 42 which supports the adjacent end 75 of the part 36, suitable bolts being provided which pass therethrough. On the left hand end of the part 37 is a flange which supports the ring 43, the latter carrying the wheel buckets of the last of the jet stages of the 80 reversing portion of the turbine. It will thus be seen that the drum carries not only the buckets of the low pressure annular stages both forward and reversing but also the wheel buckets of a forward and a reversing jet stage.

Actual practice has demonstrated that the construction shown is very efficient and reliable in operation, and that the tendency of the shaft to whip is so far eliminated that it 90 can be disregarded and small clearances between the relatively rotating parts employed. The arrangement of the drum and the cylindrical portion of the shaft is such that an exceedingly stiff construction is provided, one portion forming an annular truss 95 for bracing the other.

It is to be understood that in so far as many of the features of my invention are concerned, and particularly of the low pressure stages, it is immaterial whether the buckets operate on the impact or on the reaction principle, or partially on the impact and partially on the reaction principle.

In accordance with the provisions of the 105 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new, and desire to secure by Letters Patent of the United States, is,— 115

1. In a rotor for an elastic fluid turbine, the combination of a shaft comprising a central tubular section and end sections secured thereto, a drum mounted on and surrounding the tubular section, buckets mounted on 120 the drum, and individual bucket carrying wheels mounted on said end sections.

2. In a rotor for an elastic fluid turbine, the combination of a shaft comprising a central section and end sections secured to said central section, bucket wheels mounted on one end section for driving the shaft forward, bucket wheels mounted on the other end section for driving the shaft in the reverse direction, a drum surrounding the cen- 125 130

- tral section, and sets of buckets mounted on the drum, one set being arranged for forward driving and another for reversing. 65
3. In a rotor for an elastic fluid turbine, 5 the combination of a shaft, bucket wheels mounted on one end of the shaft for driving it in one direction, bucket wheels mounted on the other end of the shaft for driving it in the opposite direction, a drum surrounding the shaft and carried thereby, a set of buckets mounted on the drum for driving the shaft in one direction, a second set of buckets mounted on the drum for driving the shaft in the opposite direction, one set of 15 bucket wheels and a set of buckets on the drum discharging motive fluid in one direction and the remaining bucket wheels and a set of buckets on the drum discharging motive fluid in the opposite direction. 20
4. In a rotor for an elastic fluid turbine, the combination of a shaft, bucket wheels acting by impact mounted on one end of the shaft, a second set of bucket wheels also acting by impact and mounted on the opposite 25 end of the shaft, a drum mounted on the shaft, buckets acting by impact mounted on the drum, and other buckets also mounted on the drum which act by reaction. 30
5. In a rotor for an elastic fluid turbine, the combination of a shaft made up of sections secured together, a drum surrounding one of said sections, spiders carried by the shaft for supporting the drum at its ends, a set of forward driving buckets mounted on 35 one end of the drum, and a set of reversing buckets mounted on the other end. 40
6. In a rotor for an elastic fluid turbine, the combination of a shaft comprising tubular and end sections, the said end sections increasing in diameter step-by-step toward the tubular section, bucket wheels mounted on the end sections of the shaft, a drum which surrounds the said tubular section, spiders carried by the shaft which support 45 the drum, and sets of buckets mounted on the drum, one set of buckets being so disposed as to produce rotation of the shaft in a given direction and another set being so disposed as to produce rotation in the opposite direction. 50
7. In a rotor for an elastic fluid turbine, the combination of a shaft, a drum mounted thereon, sets of buckets mounted thereon which operate on the reaction principle, 55 flanges on opposite ends of the drum, and a set of buckets carried by each of said flanges that operate on the impact principle. 60
8. In a rotor for an elastic fluid turbine, the combination of a shaft having an intermediate cylindrical section and end sections attached thereto, a drum mounted on and surrounding said intermediate section, said drum being composed of two principal parts which differ in diameter, a set of forward 65 driving buckets mounted on the part of larger diameter, a set of buckets for reversing mounted on the part of lesser diameter, and spiders for supporting the drum that are carried by the shaft. 70
9. In a rotor for an elastic fluid turbine, 75 the combination of a shaft comprising a central tubular section and end sections, flanges for uniting the sections, a drum surrounding the tubular section, spiders mounted on the tubular section for supporting the drum, oppositely disposed sets of buckets mounted on the drum, and forward driving and reversing buckets mounted on the end sections of the shaft and supplying motive fluid to the buckets on the drum. 80
10. In an elastic fluid turbine, the combination of a casing comprising high, low pressure and reversing sections, diaphragms in the high pressure and reversing sections to divide the same into jet stages of expansion, bucket wheels for the jet stages, certain of the high pressure stages having a greater number of rows of buckets than the other jet stages, a shaft, a drum carried thereby, and sets of buckets mounted thereon to form 90 with coöperating intermediate buckets annular stages working on the reaction principle, one set being arranged to drive the shaft forward and the other to reverse it. 95
11. In an elastic fluid turbine, the combination of a casing divided into high, low pressure and reversing sections, diaphragms for dividing the high pressure and reversing sections into compartments, bucket wheels mounted in the compartments, a drum 100 mounted in the low pressure section, forward driving and reversing buckets mounted on the drum, and buckets also carried by the drum which extend into the high pressure and reversing sections and coöperate 105 therewith to produce rotation of the shaft. 12. In a turbine, the combination of a drum, buckets mounted thereon and arranged in sets, one for forward driving and the other for reversing, a casing for the 110 drum having an exhaust that is common to both sets of buckets, flanges carried by the casing that extend toward each other and into the conduit, intermediate buckets carried thereby, and a plurality of jet stages 115 located on opposite ends of the drum and arranged when in operation to discharge the exhaust therefrom to the drum buckets. 13. In an elastic fluid turbine, the combination of jet stages for forward driving and reversing, annular low pressure stages for forward driving and reversing, and a drum which is common to all of the annular low pressure stages and also carries buckets belonging to a portion of the jet stages. 120 14. In an elastic fluid turbine, the combination of a casing which is divided by diaphragms at opposite ends into stages or 125

wheel compartments, bucket carrying wheels in the stages, oppositely disposed bucket carrying drums, one of which receives motive fluid from the wheel or wheels at one 5 end of the casing and another of which receives motive fluid from the wheel or wheels at the other end of the casing, and an exhaust conduit opening into the space be-

tween the drums and receiving the exhaust fluid from both.

In witness whereof, I have hereunto set my hand this 23d day of July, 1907.
